 Cincinnati Grinders Incorporated, Cincinnati,
 Ohio, a corporation of Ohio

Application April 5, 1933, Serial No. 664,572

13 Claims. (Cl. 74—27)

This invention relates to improvements in machine tool structures and especially to improvements in reversing mechanisms for use therewith.

5 An object of the invention, therefore, is the provision of an improved reversing mechanism for reversing the drive to a slideable part of a machine tool organization, for example, the work supporting table of a grinding machine.

10 Another object of the invention is the provision of means for effecting a tarry or pause at or prior to each reversal of the direction of movement of the part.

15 A further object of the invention is the provision of such a mechanism that may be readily adjusted for varying the duration of the pause or tarry.

20 A still further object of the invention is the provision of an adjustable tarry mechanism that can be applied to an existing and well-known reversing mechanism without requiring an extensive re-organization or complete modification of said reversing structure.

25 Other objects and advantages of the present invention should be readily apparent by reference to the following specification considered in conjunction with the accompanying drawings, forming a part thereof, and it is to be understood that any modifications may be made in the exact 30 structural details there shown and described, within the scope of the appended claims, without departing from or exceeding the spirit of the invention.

In the drawings:

35 Figure 1 is a front elevation of a grinding machine embodying the improvements of this invention.

Figure 2 is a fragmentary sectional view taken on line 2—2 of Figure 1.

40 Figure 3 is a sectional view taken on line 3—3 of Figure 2.

Figure 4 is a fragmentary sectional view taken on line 4—4 of Figure 2.

45 Figure 5 is a fragmentary sectional view taken on line 5—5 of Figure 4.

Figure 6 is a fragmentary sectional view taken on line 6—6 of Figure 1.

Figure 7 is a fragmentary sectional view taken on line 7—7 of Figure 3.

50 Throughout the several views of the drawings similar reference characters are employed to denote the same or similar parts.

As was noted above, this invention has application to machine tool structures generally and particularly to the mechanism for reversing the

direction of movement of a work supporting table of a grinding machine. The drawings disclose the invention as applied to such a machine and as there shown the machine comprises a bed 10 having formed on the upper surface thereof a flat and a V-guideway 11 and 12 on which is mounted a work supporting table 13. Extending rearwardly from the bed 10 is an extension 14 having formed thereon guideways 15 for a grinding wheel carriage 16. Rotatably mounted in 10 the carriage 16 is a spindle supporting at its outer end a grinding wheel 17. The wheel 17 is enclosed within a suitable guard 18 secured to the carriage 16 and employed to confine the coolant usual with grinding machines.

15 The spindle is provided intermediate its bearings with a pulley or sheave for the flexible transmission belt or belts 19 which are in turn trained about a pulley or sheave secured to a shaft 20 extending from the prime mover or motor 21. The 20 motor 21 is secured to the bed extension 14 and in addition to rotating the grinding wheel and its spindle rotates through a sprocket chain transmission 22 the slideable gears of a change feed box mechanism secured to the rear end of 25 the bed extension 14. This change gear box is not illustrated in the drawings since it may be of any well-known construction through which the drive is had to a transverse shaft 23, see 30 Figure 4, extending from the rear of the machine to the front thereof.

35 The forward end of the shaft 23 is splined to a bevel pinion 24 rotatably journaled in a bracket 25 carried by a housing 26 in turn secured to the reversing plate 27. Also journaled in the bracket 25 is a sleeve 28 to one end of which is keyed or otherwise secured a bevel pinion 29 meshing with the bevel gear 24. The other end of the sleeve 28 has formed integral therewith a spur pinion 30 which meshes with the larger gear 31 of a compound gear 32 loosely journaled on a shaft 33 carried by the housing 26. The sleeve 28 ahead of the spur gear 30 has formed thereon clutch teeth 34 adapted to engage similar clutch teeth 35 formed on the opposed face 40 of a sliding gear 36. The gear 36 is splined as at 37 to a drive shaft 38 which has its one end journaled in the sleeve 27 and its other end in bearings 39 provided by the reversing plate 27. Meshing with the gear 36 is the small pinion 40 45 of the compound gear 32, as shown in Figure 4, but it is to be understood that the gear 36 may be shifted to disengage it from the pinion 40 and to intermesh the clutch teeth 34 and 35.

50 In order to shift the clutch-gear 35—36, it is

provided with a circumferential groove 41 receiving the free end 42 of a shifter fork 43 pinned or otherwise secured to a shaft 44 journaled in the housing 26. The shaft 44 projects beyond the housing 26 and has secured to its projecting portion a shift lever 45 carrying at its upper end a knob 46, see Figure 1, and at its lower end a spring pressed detent 47 co-operating with sockets 48 carried by the forward face of the housing 26. From the foregoing it will be noted that the driving shaft 38 may be driven directly through the clutch teeth 34 and 35 at the same rate of speed as the shaft 23, or may be driven through the back gear at a much slower rate of speed.

The shaft 38 has loosely journaled thereon intermediate the bearings 39 a pair of oppositely facing bevel pinions 49 and 50 respectively having formed on opposed faces clutch teeth 51 and 52. Keyed to the shaft for slidable movement relative thereto and intermediate the gears 49 and 50 is a clutch member 53 having formed on opposite faces thereof clutch teeth 54 and 55. The clutch teeth 54 are adapted to engage with clutch teeth 51, while the clutch teeth 55 are adapted to engage with clutch teeth 52 whereby, depending upon the position of the clutch 53, one or the other of the gears 49 and 50 is positively rotated.

Meshing with the gears 49 and 50 is a relatively large bevel gear 56 keyed or otherwise secured to a worm shaft 57 rotatably journaled in bearings provided by the reverse plate 27. Intermediate the ends of the worm shaft 57, there is provided a worm 58 which meshes with a worm wheel 59 loosely mounted on a vertical shaft 60. The shaft 60 is journaled in bearings 61 and 62 provided by the bed 10 and the said shaft has secured to its upper end a rack pinion 63 meshing with a rack 64 attached to the under surface of the table 13.

Also loosely journaled about the shaft 60 is a bevel gear 65 meshing with a pinion 66 pinned or otherwise secured to the inner end of a shaft 67 rotatably journaled in the reverse plate 27. The outer end of the shaft 67 has pinned or otherwise secured to it a silent chain sprocket 68 having trained thereabout a chain 69 in turn being trained about a sprocket 70 formed integral with or secured to a sleeve 71. The sleeve 71 is journaled on a shaft 72 carried by a bracket member 73 that is attached to and extends upwardly above the reverse plate 27. Secured as by a key or otherwise to the sleeve 71 is a hand wheel 74 which through the transmission just described constitutes a manual means for actuating the work table 13.

In order to connect either the power drive or manual drive with the table, the following mechanism is employed. The shaft 60 has extending through it at a point between the worm wheel 59 and bevel gear 65 a pin 75 carrying on projecting ends rollers 76. The rollers 76 are disposed in elongated perforations 77 formed through a clutch member 78 surrounding the shaft 60 and disposed intermediate the said worm wheel 59 and bevel gear 65. The clutch member 78 has formed on one end thereof clutch teeth 79 adapted to engage clutch teeth 80 formed on the gear 65. On the other end the clutch 78 is formed with clutch teeth 81 adapted to engage clutch teeth 82 provided by a clutch member 83 associated with the worm wheel 59. The clutch member 83 forms in effect a portion of a safety friction clutch drive which comprises the said

member 83, a disc 84, friction members 85, and springs and screws 86. The clutch 78 is shifted to its extreme positions to engage either clutch teeth 79-80 or clutch teeth 81-82 and for which purpose it has formed circumferentially thereof a groove 87 which co-operates with the nose 88 of the clutch shifter lever 89. This lever is adapted to be oscillated about the axis of its pivot shaft 90 by means of the lever 91 which projects beyond the forward face of the reverse plate 27. From the foregoing it will be noted that the table may either be driven by power or actuated manually by merely shifting the clutch 78. It will also be noted that when the manual means is in engagement the power means is disconnected and conversely when the power means is in engagement the manual drive is broken.

The means for shifting the table reversing clutch 53 comprises a shifter fork 92 carrying rollers 93 disposed within a circumferential groove 94 formed in the said clutch. The shifter fork is mounted on a bar 95 secured in the walls of a reverse plate cover 105. Secured to the upper end of the fork 92 is a U-shaped spring cage 96 through the arms of which is slidably a rod 97. Secured to the rod intermediate its ends is a dog 98 having formed thereon oppositely inclined cam faces 99 and 100.

Encircling the rod 97 and disposed on opposite sides of the dog 98 are springs 101 and 102 contacting with adjacent faces of the dog 98 on one end thereof and contacting on the other end with the arms of the U-shaped frame 96. The dog 98 is adapted to shift the rod 97 and compress the springs between itself and the said arms of the frame 96. In order to shift the said dog there is provided an arm 103 to which it is pivotally secured intermediate its ends, the arm being also pinned or otherwise secured to a shaft 104 journaled in the cover plate 105 of the reversing plate 27. The shaft 105 extends beyond the cover 105 and has keyed or otherwise secured to its projecting portion a reversing lever 106 which extends upwardly above the reverse plate and parts carried thereby. As seen in Figure 2, the lever 106 has projecting from it toward the bed and table an abutment 107 adapted to normally lie between opposed reversing dogs 108 and 109. The dogs 108 and 109 are adjustable along a dog rail 110 provided on the forward face of the table 13 and are positioned at a distance representative of the length of the work, so that the said dogs contact with the abutment 107 and shift the lever 106 when the grinding wheel reaches the said ends of the work.

The spring frame 96 is inclined to move simultaneously with the movement of the dog 98 and the compression of the springs 101 and 102, but this movement is restricted or prevented by latch members 111 and 112 being pivoted as at 113 to bosses 114 projecting inwardly from the cover 105. For this purpose the latches have formed intermediate their ends a shoulder 115 adapted to engage with their respective arms of the U-shaped spring frame 96. The free ends of the latches 111 and 112 are respectively provided with cam faces 116 and 117 adapted to be engaged respectively by the cam faces 99 and 100 of the dog 98 for releasing the latched engagement and permitting the springs 101 and 102 to expand or fire, thereby shifting the clutch shifter fork 92 from one position to the other.

In practice it is frequently desirable that a tarry be effected in the movement of the work table prior to the reversal thereof, so that a

complete rotation of the work relative to the grinding wheel may be had prior to said reversal. This mechanism as shown in the instant application includes means for holding the springs 101 and 102 under compression a variable time after the latches 111 and 112 have been released. However, it is necessary to permit a short movement of the shifter fork in order to disengage the clutch teeth 51—53 or 52—55 depending upon in which direction the table was moving at the time of shifting the reverse lever 106. For this reason a second pair of latches 118 and 119 is provided which are pivoted at 120 to bosses 121 projecting from the cover 105. As will be seen in Figure 3, the latch 111 has its shoulder 115 contacting with the adjacent arm of the spring frame 96 and that the second latch 119 has its nose 122 spaced a short distance from the shoulder 115 and is disposed in position to engage the said arm of the frame when released by the shoulder 115 and will, therefore, limit the movement of the frame and consequently the shifter fork upon release. This movement is designed to neutralize the clutch 53 thereby stopping the power drive to the table and arresting its movement. In time the latch nose 122 is removed so that the spring may complete its firing or shifting and shift the clutch 53 to the other end of its movement.

The time of operation of the second latch 119 is adjustably controlled and the mechanism for actuating this latch is as follows: The dog lever 103 continues upwardly above the dog 98 and is provided on its free end with a head 123 through which is formed an enlarged aperture 124 accommodating a pin 125. The pin 125 is threaded on opposite ends into the heads 126 and 127 of cylinders 128 and 129. Surrounding the pin 125 on opposite sides of the lever 103 are springs 130 and 131, the former abutting on one end with a washer 132 that contacts with the ball end 123 of the lever and on the other end with the head 126, while the latter spring 131 engages a similar washer 133 on the other side of the ball end of the lever and the head 127 of the cylinder 129. The springs 130 and 131 are adapted to be compressed simultaneously with the compression of the springs 101 and 102 and tend to shift one or the other of the cylinders 128 and 129 depending upon in which direction the spring frame 96 is to be shifted.

Disposed respectively within the cylinders 128 and 129 is a piston 134 and 135, the former being secured to a piston rod 137 extending from the left hand end of the cover 105 while the latter is secured to a piston rod 137 extending from the right hand end of the said cover 105, all as viewed in Figure 3. The cylinders 128 and 129 are respectively provided at their head ends with a check valve inlet 138 and 139 permitting the influx of air into the cylinder when the heads thereof are moving away from their respective pistons but preventing any discharge of air when moving toward their respective pistons. It is to be understood that air is an hydraulic medium and instead of using air, oil could be substituted therefor which might be included in a closed hydraulic circuit or system. The pistons and piston rods 134—136 and 135—137 are respectively provided with ports 140 and 141 which respectively terminate in a transverse port 142 and a valve chamber 143. The valve chamber in turn connecting with the atmosphere 144 in the case of air as the hydraulic medium or with a sump or tank in the case of other types of hy-

draulic systems. The valve chamber 143 has adjustable therein a needle valve, 145, thereby adjustably controlling the rate of flow through the said exhaust ports 140 or 141 and 142.

Each of the cylinder heads 127 and 126 has associated therewith an upstanding lug 146 and 147 respectively adapted to engage with an adjustable abutment, here shown as a screw 148 and 149 respectively carried by the second latches 119 and 118. The upper ends of said latches have respectively secured to them one end of a spring 150 and 151, the other ends of which are anchored to pins 152 and 153 provided by the cover 105. The springs 150 and 151 oscillate their respective latches to a position to dispose the nose 122 thereof in a position to limit the movement of the spring frame 96 and shifter fork 92 when released by the primary latches 111 and 112. In order, therefore, to accurately position the said latches, abutments 154 and 155 are provided to limit the movement of the secondary latches 118 and 119 under the influence of their springs.

The operation of the parts is as follows: Assuming the work table to be traveling in a given direction, one of the dogs 108 or 109 will engage the reversing lever abutment 107 and oscillate the said lever. The oscillation of the reversing lever will, through the clutch shifting lever 103, compress one of the clutch springs 101 and 102 and simultaneously compress one of the tarry springs 130 or 131. As soon as these springs are sufficiently compressed the dog 98 which was effecting the compression of the springs 101 and 102 will, through its cam faces 99 or 100, release the primary latch 111 or 112 which is holding the spring frame 96. Upon release of this frame, it will move under the influence of its compressed spring, which movement, however, will be but one half of its total movement, or until it is arrested by the nose 122 of the secondary latches 118 and 119. At this time the reversing clutch 53 is in its neutral position, thereby stopping the movement of the table.

The tarry spring 130 or 131 under compression now expands causing one of the lugs 146 or 147 to engage with its adjustable abutment 148 or 149 and oscillate the secondary latch 118 or 119 about its pivot 120. At this time the hydraulic medium between the piston 134 or 135 and the head of the cylinder being moved will be forced outwardly through the ports 140 or 141 and 142 past the valve 145. The adjustment of this valve 145 determining the rate of escape of the hydraulic medium and consequently determining the rate of movement of the cylinder. This rate of movement determining the time between the neutralizing of the clutch and the engagement thereof with the opposite clutch member. As the head and cylinder continue to move, the secondary latch will be oscillated to dispose its nose 121 above the spring frame 96 thereby releasing the said frame and permitting the compressed spring 101 or 102 to complete the shifting of the clutch. It is to be understood that upon reverse movement of these parts the chamber between the piston and its cylinder head is again filled by drawing the hydraulic medium through the one-way check valves 138 and 139.

What is claimed is:

1. In a grinding machine of the class described the combination with a bed, a table mounted thereon for movement relative thereto in opposite directions, and a mechanical drive mechanism for effecting the said movements of the

- table, of means operable by the table for effecting the reversal thereof, and hydraulically controlled means operable with the reversing means for delaying the operation of said means and thereby effecting a tarry in the movement of the table prior to each reversal thereof.
2. In a grinding machine of the class described the combination with a bed, a table mounted thereon for movement relative thereto in opposite directions, and a mechanical drive mechanism for effecting the said movements of the table, of means operable by the table for effecting the reversal thereof, and hydraulically controlled means operable with the reversing means for delaying the operation of said means and thereby effecting a tarry in the movement of the table prior to each reversal thereof, said hydraulic tarry means comprising a piston and cylinder mechanism for each end of the movement of the table.
3. In a grinding machine of the class described the combination with a bed, a table mounted thereon for movement relative thereto in opposite directions, and a mechanical drive mechanism for effecting the said movements of the table, of means operable by the table for effecting the reversal thereof, and hydraulically controlled means operable with the reversing means for delaying the operation of said means and thereby effecting a tarry in the movement of the table prior to each reversal thereof, said hydraulic tarry means comprising a piston and cylinder mechanism for each end of the movement of the table, each of the piston and cylinder mechanisms including an inlet for the hydraulic medium, and a variably controlled outlet whereby the tarry may be changed or varied.
4. In a reversing mechanism for use with machine tool organizations, the combination of a table member or slide, a reversible mechanical drive for said table, a load and fire mechanism for effecting the reverse of the drive, and means for controlling the operation of said load and fire mechanism including a pivoted latch, a yieldably actuated member for actuating the latch to its released position, and hydraulic means for controlling the movement of the latch release member.
5. In a reversing mechanism for use with machine tool organizations, the combination of a table member or slide, a reversible mechanical drive for said table, a load and fire mechanism for effecting the reverse of the drive, and means for controlling the operation of said load and fire mechanism including a pivoted latch, a yieldably actuated member for actuating the latch to its released position, and hydraulic means for controlling the movement of the latch release member, said hydraulic control means including a piston and cylinder movable relative to one another, one of said parts carrying the latch actuating member, and means controlling the flow of an hydraulic medium employable with the piston and cylinder mechanism.
6. In a reversing mechanism for use with machine tool organizations, the combination of a table member or slide, a reversible mechanical drive for said table, a load and fire mechanism for effecting the reverse of the drive, and means for controlling the operation of said load and fire mechanism including a pivoted latch, a yieldably actuated member for actuating the latch to its released position, and hydraulic means for controlling the movement of the latch release member, said hydraulic control means including a piston and cylinder movable relative to one another, one of said parts carrying the latch actuating member, and an hydraulic medium for effecting the operation of the piston and cylinder mechanism, a valve controlled inlet for the medium to the piston and cylinder mechanism, and an adjustable valve controlled outlet for the medium whereby the operation of the piston and cylinder mechanism under the yielding means is controlled for correspondingly effecting and determining a tarry in the movement of the table and the duration thereof.
7. In a reversing mechanism for use in controlling the reversal of a member of a machine tool organization the combination with the said member, and a reversible mechanical drive to said member, of a reversing mechanism for said drive including a clutch shiftable to two operable positions and having a neutral position intermediate same, a load and fire mechanism operable by the table for effecting the movement of the clutch from one operative position to the other, and means operable on said load and fire mechanism to limit its movement and stop the clutch in its neutral position thereby stopping the movement of the table and subsequently releasing said load and fire mechanism to permit the load and fire mechanism to complete its movement.
8. In a reversing mechanism for use in controlling the reversal of a member of a machine tool organization the combination with the said member, and a reversible mechanical drive to said member, of a reversing mechanism for said drive including a clutch shiftable to two operable positions and having a neutral position intermediate same, a load and fire mechanism operable by the table for effecting the movement of the clutch from one operative position to the other, and means operable on said load and fire mechanism to limit its movement and stop the clutch in its central position thereby stopping the movement of the table and subsequently releasing said load and fire mechanism to permit the load and fire mechanism to complete its movement, said means including a stop latch, and yielding means for rendering the stop latch inoperative.
9. In a reversing mechanism for use in controlling the reversal of a member of a machine tool organization the combination with the said member, and a reversible mechanical drive to said member, of a reversing mechanism for said drive including a clutch shiftable to two operable positions and having a neutral position intermediate same, a load and fire mechanism operable by the table for effecting the movement of the clutch from one operative position to the other, and means operable on said load and fire mechanism to limit its movement and stop the clutch in its neutral position thereby stopping the movement of the table and subsequently releasing said load and fire mechanism to permit the load and fire mechanism to complete its movement, said means including a stop latch, yielding means for rendering the stop latch inoperative, and an hydraulically controlled piston and cylinder mechanism for controlling the operation of the stop latch.
10. In a reversing mechanism for use in controlling the reversal of a member of a machine tool organization the combination with the said member, and a reversible mechanical drive to said member, of a reversing mechanism for said drive including a clutch shiftable to two operable positions and having a neutral position intermediate same, a load and fire mechanism operable by

- the table for effecting the movement of the clutch from one operative position to the other, and means operable on said load and fire mechanism to limit its movement and stop the clutch in its neutral position thereby stopping the movement of the table and subsequently releasing said load and fire mechanism to permit the load and fire mechanism to complete its movement, said means including a stop latch, yielding means for rendering the stop latch inoperative, an hydraulically controlled piston and cylinder mechanism for controlling the operation of the stop latch, and yielding means for returning the stop latch to its normal operative position.
11. In a reversing mechanism for use with machine tool organizations to effect and control the reversal of a member thereof the combination with the said member, and a reversible drive connected therewith, of a reversing mechanism for said drive including a clutch member, a load and fire mechanism for shifting the clutch from one to the other of its operative positions, an arm for actuating the load and fire mechanism through a portion of its movement, a stop latch for limiting the movement of the load and fire mechanism and stopping the clutch in its neutral position, yielding means for rendering the stop latch inoperative, and a connection between the stop latch yielding means and arm whereby said yielding means is tensioned simultaneously with the partial operation of the load and fire mechanism.
12. In a reversing mechanism for use with machine tool organizations to effect and control the reversal of a member thereof the combination with the said member, and a reversible drive connected therewith, of a reversing mechanism for said drive including a clutch member, a load and fire mechanism for shifting the clutch from one to the other of its operative positions, an arm for actuating the load and fire mechanism through a portion of its movement, a stop latch for limiting the movement of the load and fire mechanism and stopping the clutch in its neutral position, yielding means for rendering the stop latch inoperative, a connection between the stop latch yielding means and arm whereby said yielding means is tensioned simultaneously with the partial operation of the load and fire mechanism, and hydraulically controlled means for controlling the operation of the stop latch actuating means, said hydraulically controlled means including a piston and cylinder, an hydraulic medium therefor, abutments on the piston and cylinder and stop latch, and a valve controlling the flow of the medium.
13. In a reversing mechanism for use with machine tool organizations to effect and control the reversal of a member thereof the combination with the said member, and a reversible drive connected therewith, of a reversing mechanism for said drive including a clutch member, a load and fire mechanism for shifting the clutch from one to the other of its operative positions, an arm for actuating the load and fire mechanism through a portion of its movement, a stop latch for limiting the movement of the load and fire mechanism and stopping the clutch in its neutral position, yielding means for rendering the stop latch inoperative, a connection between the stop latch yielding means and arm whereby said yielding means is tensioned simultaneously with the partial operation of the load and fire mechanism, and hydraulically controlled means for controlling the operation of the stop latch actuating means, said hydraulically controlled means including a piston and cylinder, an hydraulic medium therefor, abutments on the piston and cylinder and stop latch, and a valve controlling the flow of the medium.

ALFRED G. PLIMMER.
